PLAYGROUND CLIMBER OR THE LIKE

Frank J. Stefe, Milwaukee, Wis., assignor to Safway Steel Products, Inc., Milwaukee, Wis., a corporation of Wisconsin

Filed Apr. 11, 1963, Ser. No. 74,396

Term of patent 14 years

(Cl. D34—5)

FIG. 1 is a perspective view of the playground climber or the like showing my new design;

FIG. 2 is a reduced side elevational view; and

FIG. 3 is a top plan view of FIG. 2.

I claim:

The ornamental design for playground climber or the like, as shown.
